COLLAPSIBLE DRESSING COMPARTMENT

Clyde Sinning, Elkhart, Ind.

Application February 9, 1932. Serial No. 591,880

10 Claims. (Cl. 135—5)

The primary object of my invention is to provide a novel dressing compartment so constructed that a removable shelf may be used with it when desired and which is therefore convenient for 5 the various uses for which it is intended.

Another object of my invention is to provide a collapsible dressing compartment of suitable construction so that it can be quickly and easily erected or collapsed by one person, and which 10 when collapsed can be carried or stored in the smallest possible space.

It is also an object of my invention to provide a dressing compartment at a bathing beach adapted to avoid wholly the danger of contagion 15 of athlete's foot.

It is also an object of my invention to provide the novel combination and arrangement of parts disclosed in the accompanying drawings and to 20 provide novel means for securing the structure in erected position and to permit of its being readily collapsed.

I attain these and other objects of my invention by the mechanism illustrated in the accompanying drawings, in which,—

25 Figure 1 is a perspective view of the invention erected for use, a portion of the fabric covering being cut away to show the interior structure;

Fig. 2 is a partial end view of the frame shown in Fig. 1 folded, with the cover removed and 30 therewith a side elevation of same in collapsed position with the spring hooks fastened to the frame;

Fig. 3 is a detail view of one of the three corners having a bent end, showing how this bent 35 end is shaped;

Fig. 4 is a detail perspective view of the fourth corner which is detachable to permit of collapsing the frame, this corner also showing one of the legs by which the structure is anchored 40 in place;

Fig. 5 is a detail perspective view of a corner (there being two such corners) having one of the flat bars bent to form a ninety-degree elbow so 45 that when the device is folded one half of the frame will be thrown away from the other half far enough to allow the two halves of the frame to fold parallel, as shown in the upper illustration of Fig. 2;

50 Fig. 6 is a perspective view of a collapsible shelf adapted for use with my invention;

Fig. 7 are detail views, the upper in section and the lower in side elevation, of the side braces and the bracket that is fastened on the columns 55 to hold and hinge the braces;

Fig. 8 is a vertical section of one of the joints used in the columns;

Fig. 9 is a section on line 9—9 of Fig. 8;

Fig. 10 is a side elevation of an improved and modified form of my invention;

Fig. 11 is a detail section on line 11—11 of Fig. 10;

Fig. 12 is a detail side elevation of one of the brackets and hinged braces;

Fig. 13 is a detail view of the brace.

Like numerals designate like parts in each of the several views.

Referring to the accompanying drawings, I provide bars 2, 3, 4 and 5 and on bars 3 and 5 are mounted the four telescopic posts 1 at the upper end of which are mounted similar bars 2, 3, 4 and 5 which form the frame work of the compartment. I provide a suitable fabric covering 7 suitably fastened to the bars 2, 3, 4 and 5 as by cover fasteners 6. Mounted on the lower set of bars are suitable pointed rods 8 which may be pushed into the ground to prevent the compartment from being easily overturned.

As shown in Fig. 3, at three corners of the compartment the bars are hingedly or pivotally connected by the bolts 9 and are spaced by the three-sixteenth inch spacers 10 which are used to provide room for the cover fasteners. The ends of the bars are provided with over-lapping projecting tongues 11 which engage the outer edge of the contiguous bar and prevent the bars from being swung to more than a 90 degree angle relative to each other.

At the fourth corner, as illustrated in Fig. 4, I provide a slot 12 to engage under and around a portion of the head screw 13' as illustrated and by which the frame work is readily fastened in or disengaged from its assembled position. At one corner on each set of the framework sections there is provided a bent end portion 14 as shown in Fig. 5, this construction being provided so that when folded one-half of the frame will be thrown away from the other half far enough to allow the two halves of the frame to fold parallel as shown in the top view of Fig. 2. At this joint also there is provided the three-sixteenth inch spacer 10 and this bar also is provided with projecting outer tongues 11 to prevent the joint from opening more than 90 degrees.

As shown in Fig. 6, I may provide a collapsible shelf 15. It is fastened to the posts 1 by suitable brackets 16 and by braces 17 which are removably seated in the sockets 18 of the lower brackets 19. The top ends of the braces are hinged to the

shelf and the shelf is hinged at 20 to the bracket 16.

Referring to Figs. 1 and 7 of the drawings, I provide side braces 21 pivotally attached by bolts 5 22 to suitable brackets 23 fastened on the posts or columns 1.

Referring to Figs. 8 and 9 of the drawings, there are illustrated sectional views of the self-supporting joint used in the telescopic columns 1. These 10 columns are made of tubing and are in three sections. Each section of tubing is enough smaller than the section below to allow them to telescope. The joint is slotted at 24 so that the end of the tube has six sections, three sections 26 remaining straight and three sections 25 formed to have the 15 projections, as shown in Fig. 9, which project out far enough so that the outside dimension is a few thousandths of an inch larger than the inside dimension of the tubes they slip into, thus 20 making a tight-slip fit after the washer 27 is slipped in the bottom end and the three straight sections 26 soldered to washer 27. The three sections with the projections 25 must have a springing effect which naturally causes a slight end motion and in not soldering these three sections to the washer this operation is made possible.

I also provide a sleeve 28 soldered higher up on the inner tube. The guide sleeve 28 takes the 30 strain off the sections, and the top sleeve 28 also acts as a stop when pulled against the sleeve 29 which is soldered in the end of the outside tube; as shown in Fig. 8.

Referring to Figs. 10-13, there is illustrated an 35 improved brace 30 pivoted at 31 to the bracket 13 in place of the brace 21. This brace 30 is provided with a laterally bent end 32 which in turn is provided with a slot 33 to engage the corresponding brace 30 hinged from the adjacent column, 40 the slotted ends of the respective braces being reversely bent so as to form a self lock of one brace on the other.

When the compartment is not in use it can be 45 folded into compact form by releasing the screws 13 and folding the bars 2, 3, 4 and 5 in the manner shown in Fig. 2, and securing them with spring hooks 36, as shown in Fig. 2, and telescoping the columns 1 within each other, thus permitting of folding the frame work of the compartment 50 into a compact bundle.

It is within the contemplation of my invention to provide a detachable top cover 34 and a detachable floor 35 so that the device can be sold either with or without the top cover or floor.

The cover is to be closed when not in use and this can be accomplished by suitable cover fasteners such as the narrow tapes 6 sewed to the cover and used as ties or by other suitable means 55 such as zippers, snap fasteners or buttons not shown.

What I claim is:—

1. In a collapsible compartment of the class described, the combination of four telescopic corner columns, each of the sections of the aforesaid telescopic columns having at one end a self-supporting joint, a foldable top section to which the upper ends of the columns are attached at points slightly spaced from the corners, foldable bottom section to which the lower ends of the bottom columns are affixed, the columns being positioned adjacent the corners of the sections, brackets mounted on the aforesaid columns and braces hingedly connected to said brackets and of suitable length so that their lower ends will engage the ground or floor.

2. In a collapsible compartment of the class described, the combination of a hingedly connected set of bars forming a bottom supporting section, a second set of hingedly connecting bars forming a top supporting section and adapted to support a fabric cover extended from the upper set of bars, telescoping columns affixed to the lower set of bars and supporting the upper set of bars to form the frame work for the compartment, and pointed legs mounted on the bottom side of the bottom supporting section for insertion in the ground to anchor the structure.

3. A collapsible compartment comprising a foldable lower section consisting of four hingedly connected bars, an upper section consisting of four hingedly connected bars, each of said sections having one bar with a right angle bend to permit of folding the bars flat against each other when in collapsed position, telescopic columns connecting the two sections said columns engaging the top and bottom sections at points spaced from the corners thereof and adapted to support a fabric covering secured to the upper section so that the structure can be collapsed without removing the cover.

4. A collapsible compartment comprising a foldable lower section consisting of four hingedly connected bars, an upper section consisting of four hingedly connected bars, each of said sections having one bar with a right angle bend to permit of folding the bars flat against each other when in collapsed position, telescopic columns connecting the two sections and adapted to support a fabric covering secured to the upper section so that the structure can be collapsed without moving the cover, three of the bars of the upper and lower sections, each having a projecting downwardly extending tongue engaging over the adjacent bar to prevent opening the frames more than 90 degrees.

5. In a collapsible compartment of the class described, the combination of a hingedly connected set of bars forming a bottom supporting section, a second set of hingedly connecting bars forming a top supporting section, and adapted to support a fabric cover extended from the upper set of bars, telescoping columns affixed to the lower set of bars and supporting the upper set of bars to form the frame work for the compartment, the hinged joints of each of the respective sections having spacers positioned therein to permit of folding the sections together without interfering with the fasteners securing the cover to the sections.

6. In a collapsible compartment of the class described, the combination of a hingedly connected set of bars forming a bottom supporting section, a second set of hingedly connecting bars forming a top supporting section, and adapted to support a fabric cover extended from the upper set of bars, telescoping columns affixed to the lower set of bars and supporting the upper set of bars to form the frame work for the compartment, brackets on the respective columns, braces hingedly mounted to said brackets, said braces each having a laterally bent slotted end adapted to interlock with a similar brace to brace the structure in its assembled position.

7. In a collapsible compartment of the class described, the combination of four telescopic supporting columns, each of the sections of the aforesaid telescopic columns having at one end a self-supporting joint, a foldable top section to which the upper ends of the columns are attached; a foldable bottom section to which the lower ends of

the columns are affixed, the columns being positioned at points only slightly spaced from the corners of the sections and laterally thereof to permit of convenient assembling and disassembly of the structure.

8. In a collapsible dressing compartment, the combination of four telescopic columns, each of the sections of the aforesaid telescopic columns having at one end a self-locking and self-supporting joint, a laterally foldable top section to which the upper ends of the columns are attached, a laterally foldable bottom section to which the lower ends of the bottom columns are affixed, the columns being positioned adjacent to and offset 15 from the corners of the sections.

9. In combination with the apparatus defined in claim 8, pointed legs mounted on the bottom side of the bottom supporting section for insertion in the ground to anchor the structure, and braces hingedly connected to the lower sections of the columns and of suitable length to engage the ground or floor in spaced relation to the foldable bottom section.

10. In combination with the apparatus defined in claim 8, brackets attached to the telescopic columns, braces pivotally attached to the brackets, said braces having laterally bent ends, said ends being slotted to form a self-lock of one brace on the other.
